UNITED STATES PATENT OFFICE.

FRANK N. ETHRIDGE, OF LYNN, MASSACHUSETTS, ASSIGNOR OF ONE-HALF TO JAMES A. WENSLEY, OF LYNN, MASSACHUSETTS.

BEADING AND SEAM-HAMMERING MACHINE.

1,123,183.

Specification of Letters Patent. Patented Dec. 29, 1914.

Application filed January 28, 1914. Serial No. 814,950.

To all whom it may concern:

Be it known that I, FRANK N. ETHRIDGE, a citizen of the United States, and resident of Lynn, in the county of Essex and State of Massachusetts, have invented certain new and useful Improvements in Beading and Seam-Hammering Machines, of which the following is a specification.

This invention relates to a machine for perfecting the seam formed by sewing together two layers forming a part of a boot or shoe or other article, the layers being sewed together wrong side out and subsequently turned right side out. A beading machine is equipped with thin, flat-sided turning arms, usually called "irons", which are oscillated in parallel planes side by side and act in a well known manner between the sewed layers after they have been turned right side out, and impart a smooth form to the seam. A machine of this character is also equipped with means for hammering or flattening the seam, said means including a bed or anvil and a hammer coöperating therewith.

One object of my invention is to provide improved mechanism for simultaneously oscillating the beading irons in a positive manner without the employment of a spring or springs.

Another object of the invention is to provide improved means for imparting to one of the irons a combined vertical reciprocating movement and a substantially horizontal oscillating movement, the other iron having only a substantially horizontal oscillating movement.

Another object of the invention is to provide certain improvements relating to the hammer and the means for operating it, whereby the force of the hammer blow may be varied within considerable limits and the acting face of the hammer cushioned to prevent the possibility of injury to the work by excessive hammer pressure.

To these and other related ends the invention consists in the improvements which I will now proceed to describe and claim.

Of the accompanying drawings forming a part of this specification: Figure 1 represents a front end elevation of a machine embodying my invention, parts of the casing being broken away; Fig. 2 represents a section on line 2—2 of Fig. 1; Fig. 3 represents a section on line 3—3 of Fig. 2; Fig. 4 repre-

sents a section on line 4—4 of Fig. 2, and a plan view of the parts below said line; Fig. 5 represents a section on line 5—5 of Fig. 2; Fig. 6 represents a section on line 6—6 of Fig. 2; Fig. 7 represents a section on line 7—7 of Fig. 6; Fig. 8 represents a section on line 8—8 of Fig. 2; Fig. 9 represents a section on line 9—9 of Fig. 2; Fig. 10 represents a section on line 10—10 of Fig. 2, and a plan view of parts below said line; Figs. 11 and 12 are side views of the turning irons shown separately, the movements of the two irons being illustrated by full and dotted lines.

The same or similar characters indicate the same parts in all the views.

12 and 13 represent the turning irons which are thin, flat-sided arms located side by side in rubbing contact with each other as usual.

The inner iron 13 has a tubular fulcrum stud 14 (Fig. 2) journaled in a bearing 15 in a post 16 on the supporting frame or casing 17, the iron 13 being oscillated horizontally between the two extremes of movement represented by Fig. 12, by the mechanism hereinafter described.

The outer iron 12 has a vertically elongated slot 18 which receives a block 19 supported by a stud 20 which is fitted to turn in the tubular fulcrum stud 14. The outer iron 12 is not only oscillated horizontally but is also reciprocated vertically by the mechanism hereinafter described, said iron being movable vertically on the block 19, while oscillating horizontally, as indicated by full and dotted lines in Fig. 11.

The frame or casing of the machine includes a face plate 22 having a recess 23 in which the irons move as described, said face plate being attached by screws 24 to the body of the frame. An adjustable gib 25 backed by set screws 26 bears on the outer side of the iron 12 and holds it in close rubbing contact with the iron 13.

The irons 12 and 13 are oscillated by a reciprocating head which moves in a path substantially at right angles with the path in which the irons oscillate, and has means for positively converting its reciprocating movement into oscillating movements of the irons. Said head as here shown includes two reciprocating slides or members 27 (Fig. 6) movable in fixed guides 29 in a thickened portion of the frame, and each provided

with an oblique tongue 28 at its outer end. Said guides constitute the means hereinafter referred to for guiding the head and the members 27 in rectilinear paths which are substantially at right angles with the paths in which the irons oscillate. Said tongues pass through vertically elongated slots 30 (Fig. 1) in the shanks 12^a, 13^a of the irons 12 and 13, and are oppositely slanted as shown by Fig. 6, so that when they are reciprocated in unison they oscillate the irons positively and simultaneously in opposite directions, the tongues 28 constituting motion-converting members.

15 The reciprocating head also includes a carrier 31 engaged with the inner ends of the slides 27, said carrier having a transverse slot 32 which receives the inner ends of the slides, and ears 33 which enter peripheral grooves 34 (Fig. 7) in the slides 27, provision being thus made for detachably engaging the carrier with the slides.

35 represents the driving shaft which is journaled in bearings 36 on the frame, and has an eccentric 37 (shown by dotted lines in Fig. 4) the strap 38 of which is connected by a rod 39 with the carrier 31. The rotation of the shaft therefore reciprocates the tongues 28 in unison. The driving shaft 35 is provided with another eccentric 40 which forms a part of the mechanism for vertically reciprocating the outer iron 12. The strap 41 of the eccentric 40 is connected by a rod 42 with an arm 43 attached to a 35 rockshaft 44 journaled in bearings in the frame. To the rockshaft 44 is attached a tubular arm 45, receiving a stud 46 which is pivoted at 46^a to a link 47. Said link is pivotally engaged with a stud 48 attached to the lower end of the shank of the outer iron 12.

The arm 43, rockshaft 44 and tubular arm 45 constitute a bell crank lever which is oscillated by the eccentric 40.

45 The stud 46 is slidable endwise and adapted to turn axially in the arm 45, said stud, the pivot 46^a, the link 47, and the stud 48 constituting a universal joint connection between the said bell crank lever and the longitudinally movable iron 12, which imparts a vertical reciprocating movement to the iron 12 when the said bell crank lever is oscillated.

It will now be seen that simple mechanism is provided for positively moving the irons 12 and 13 in the various directions described, said mechanism being free from springs and accurately controlling the movements of the irons.

50 The rear portion of the frame is extended upwardly to form a raised standard which is provided with an anvil 50 and with an arm 51 having a vertical guide 52. In said guide is a vertically adjustable fulcrum block 53 preferably made of two sections of

steel clamped together by screws 54 (Fig. 5) and having recesses in their meeting faces to receive the rounded end of a hammer lever 55, said end being adapted to turn in the fulcrum block.

70 The hammer lever 55 is provided with a head adapted to coöperate with the anvil 50 in flattening a seam placed on the anvil. As here shown the head is formed by an enlargement 58 of the lever 55, said enlargement having a recess 59 and a spring receiving chamber 60, and an acting member 61 having a hammer face opposed to the face of the anvil. The member 61 has a stem 62 extending through the chamber 60 and provided with an adjustable stop shoulder normally held by a spring 63 against the upper end of the enlargement 58, said shoulder being preferably a nut 64 engaged with a threaded portion of the stem 62 and confined against accidental rotation thereon by a lock nut 65. The spring 63 is seated at one end on the inner end of the chamber 60 and at the other end on the hammer member 61, and yieldingly projects the acting 80 face of said member from the recess 59 to an extent determined by the adjustment of the shoulder or nut 64. The member 61 is therefore adapted to strike the work yieldingly.

95 The hammer lever is connected by a rod 66 with the eccentric strap 38 so that the rotation of the eccentric 37 oscillates the hammer.

90 The fulcrum block 53 is vertically adjustable in the guide 52, to vary the limit of the downward movement of the hammer face in accordance with the thickness of the work, so that when the work is of maximum thickness the fulcrum block may be adjusted to cause a relatively wide separation of the hammer face from the anvil at the end of its downward movement. To this end the fulcrum block is adjustably confined between a stop screw 69 engaged with a threaded orifice in a cap 70 secured in the upper end of the guide 52 and bearing on the upper end of the fulcrum block, and a spring 71 interposed between the lower end of the fulcrum block and a follower 72 in the lower portion 115 of the guide 52. The follower is supported by an adjusting screw 73 engaged with a threaded orifice in the lower end of the guide, and confined against accidental rotation by a lock nut 74. The screws 69 and 73 are adapted to be adjusted to vary the height of the fulcrum block as will be readily seen. A downward adjustment of the fulcrum block increases the width of the space between the hammer member 61 and the anvil 125 when said member reaches the downward limit of its throw, while an upward adjustment of the fulcrum block decreases the width of said space. The spring 71 enables the fulcrum block to yield downwardly 130

when the hammer face is in contact with the work and the rod 66 is at the same time exerting a downward pull on the hammer, so that said spring also tends to cushion the 5 blow of the hammer, the cushioning action being regulable by the screw 73.

The rod 42 is adjustable in length to enable the limits of the longitudinal movement of the iron 12 to be adjusted, said rod 10 being composed of a central section having a right-hand thread at one end and a left-hand thread at the other end, and end sections 42^a and 42^b which are tapped to engage said threaded ends, so that rotation of the 15 central section shortens or lengthens the rod.

The slot 30 in the shank of the vertically movable iron is elongated sufficiently to permit the vertical movement of the iron 12 and 20 the various adjustments of the limits of said movement permitted by the described construction of the rod 42.

I claim:—

1. A machine of the character stated, comprising a pair of oscillatory turning irons, one of said irons being movable longitudinally when oscillating, a head having members adapted to positively convert a reciprocating motion of the head into an oscillating motion of the irons, means for guiding said head and motion-converting members in rectilinear paths substantially at right angles with the paths in which the irons oscillate, connections between said head and the shaft whereby the head is reciprocated, and connections between the shaft and the longitudinally movable iron whereby the latter is longitudinally reciprocated while oscillating.

2. A machine of the character stated, comprising a pair of oscillatory turning irons, one of which is also movable longitudinally, said irons having slotted shanks, a head movable in a path substantially at right angles with the paths in which the irons oscillate and having oppositely slanted oblique motion-converting members engaged in the slots in said irons, a driving shaft, connections between the head and shaft whereby the head is reciprocated, and connections between the shaft and the longitudinally movable iron whereby the latter is reciprocated longitudinally when oscillating, said last named connections including 45 a bell crank lever arranged to be oscillated by the driving shaft and a universal joint connection between said lever and the longitudinally movable iron.

3. A machine of the character stated, comprising a supporting frame having an upwardly projecting standard, an anvil and a fulcrum guide located side by side on the upper end of the standard, a fulcrum block movable in said guide, a stop adjustably engaged with the guide and positively limit-

ing the movement of the fulcrum block in one direction, means for holding the fulcrum block against said stop, a hammer lever mounted at one end to swing on the fulcrum block and having an acting face at its opposite end opposed to the anvil, and means for oscillating the hammer lever.

4. A machine of the character stated, comprising a supporting frame having an upwardly projecting standard, an anvil and a fulcrum guide located side by side on the upper end of the standard, a fulcrum block movable in said guide, a stop adjustably engaged with one end of the guide and positively limiting the movement of the fulcrum block in one direction, a spring seated on the opposite end of the guide and holding the fulcrum block against said stop, a hammer lever mounted at one end to swing on the fulcrum block and having an acting face at its opposite end opposed to the anvil, and means for oscillating the hammer lever.

5. A machine of the character described, comprising a pair of oscillatory turning irons having slotted shanks, one of said irons being longitudinally movable while oscillating, and the slot in the shank thereof being elongated, a movable head having members adapted to positively convert a reciprocating motion of the head into an oscillating motion of the irons, means for guiding said head and members in rectilinear paths substantially at right angles with the paths in which the irons oscillate, connections between said head and shaft whereby the head is reciprocated, and connections between the shaft and the longitudinally movable iron whereby the latter is longitudinally reciprocated while oscillating, said connections including a bell crank lever, a universal joint connection between said lever and the longitudinally movable iron, an eccentric on the shaft, and a rod connected with the strap of said eccentric and with one arm of the bell crank lever, said rod being adjustable in length to adjust the limits of the longitudinal movement of the last mentioned iron.

6. A machine of the character stated, comprising a pair of oscillatory turning irons having slotted shanks, one of said irons being longitudinally movable, a head having oppositely slanted oblique motion-converting members engaged with the slots in said irons, means for guiding said head and members in rectilinear paths substantially at right angles with the paths in which the irons oscillate, a driving shaft, connections between the head and shaft whereby the head is reciprocated, and connections between the shaft and the longitudinally movable iron whereby the latter is longitudinally reciprocated while oscillating, said connections including a bell crank lever and a universal joint connection between said lever and the longitudinally movable iron.

and the longitudinally movable iron, an eccentric on the shaft, and a rod connecting the strap of said eccentric with one arm of the bell crank lever, said rod being adjustable in length to adjust the limits of the longitudinal movement of the last mentioned iron, and the slot in said iron being elongated to permit said longitudinal move-

ment and various adjustments of the limits thereof.

In testimony whereof I have affixed my signature, in presence of two witnesses.

FRANK N. ETHRIDGE.
